(57) **CLAIM**

The ornamental design for a bathroom utensil, as shown and described.

DESCRIPTION

FIG. 1 is a perspective view showing my new design for a bathroom utensil;
 FIG. 2 is a front elevational view thereof; the rear elevational view being identical to FIG. 2;
 FIG. 3 is a right side elevational view thereof; the left side elevational view being identical to FIG. 3;
 FIG. 4 is a top plan view thereof; and,
 FIG. 5 is a bottom plan view thereof.

(Continued)

The parts delineated in dashed lines form no part of the claimed design.
